APPARATUS FOR ELECTROPLATING WIRE

John S. Nachtman, Youngstown, Ohio

Application February 15, 1943, Serial No. 475,908

7 Claims. (Cl. 204—206)

The invention relates generally to the electroplating of wire, and more particularly to the continuous electroplating of wire and the like to produce a uniform and adherent coating.

In the conventional practice of electroplating wire the plating anodes do not completely surround or encircle the wire, and are located at a substantial distance from some parts of the wire in the plating solution. This arrangement requires a high electroplating voltage and tends to produce polarization at the electrodes, which not only sets up increased resistance to the flow of plating current, but causes evolved gas to accumulate on the surface of the wire, and such accumulated gas produces rough deposits in the coating which crack and peel off when the wire is sharply bent after coating.

Moreover, in conventional practice the current density which can be used is limited by the heating effect of the current on the solution and the wire, and consequently the rate of electroplating is correspondingly limited.

Furthermore, in conventional electroplating of wire, the wire is often reeved up and down a number of times during the plating operation, and this requires added equipment which in the case of heavy gauge wire is heavy and expensive both as to initial cost and maintenance.

I have overcome these difficulties by utilizing a tubular preferably cylindrical anode completely encircling the moving wire being electroplated, and by constantly rotating said anode to subject every part of the wire surface to the same anode conditions, while circulating plating solution through the tubular anode at a rate calculated to maintain ideal plating conditions.

It is therefore a general object of the present invention to provide novel apparatus and methods for electroplating wire, so as to overcome all the disadvantages present in prior practice.

A more specific object is to provide for continuously electroplating wire with a minimum of electroplating voltage.

Another object is to provide for increasing the current density which can be used in electroplating wire and thus produce a higher rate of electroplating.

Another object is to provide for substantially eliminating polarization at the electrodes during the electroplating of wire.

A further object is to provide an improved method and apparatus for electroplating wire in which the wire travels in a straight horizontal path.

A still further object is to provide a high speed

economical method of producing electroplated wire having a uniform, fine-grained and adherent coating which will stand severe bending without peeling or cracking.

These and other objects which will be apparent from the following description are accomplished by the improvements comprising the present invention, which is illustrated by way of example in the accompanying drawings and herein described and claimed.

Referring to the drawings—

Figure 1 is a diagrammatic side view on a small scale of a complete wire electroplating line embodying the present invention;

Fig. 2 is an enlarged somewhat diagrammatic longitudinal view, partly in section and partly in elevation, of a preferred embodiment of one of the units for carrying out the electroplating step of the invention;

Fig. 3 is a transverse sectional view as on line 3—3, Fig. 2;

Fig. 4 is a transverse sectional view as on line 4—4, Fig. 2; and

Fig. 5 is a transverse sectional view as on line 5—5, Fig. 2.

Similar numerals refer to similar parts throughout the drawings.

For convenience, the invention is shown and described as applied to the electroplating of steel wire with zinc, but it is obvious that within the scope of the appended claims the invention is applicable with slight modifications to the electroplating of wire with a variety of other metals.

For example, in plating wire with a heavy deposit of copper, it is advantageous to use a copper cyanide strike in a section of my novel plating apparatus, followed by a water rinse, and then to use an acid copper electrolyte in one or more additional sections of my novel plating apparatus.

Also, for obtaining very heavy plating deposits with relatively fine-grained structure, it is desirable to plate alternately from alkaline and acid electroplating solutions in separate sections or units of my novel plating apparatus with thorough water rinsing between sections.

Referring first to Figure 1, wires W are fed continuously to the electroplating line in a well known manner, as by motor driven feed rolls 7, which pull the wires from a plurality of pay-off reels indicated at 8 and 9, over guiding rollers 10, 11 and 12. From the guide rollers, the wires pass through a welder 13, a straightening machine 14 and feed rolls 7 into and through a looping pit 15 to the feed rolls 16.

The wires are pulled continuously at substan-

tially constant speed from the feed rolls 16 through the rest of the apparatus by the pulling rolls 17, and other rolls in the line may be synchronously driven if desired. When a coil from reels 8 or 9 is completely paid out, the feed rolls 7 are temporarily stopped while the end of a new coil is butt welded at 13 to the trailing end of the wire paid out, during which operation wire is fed from the looping pit 15 to the feed rolls 16. Rolls 7 are then accelerated to feed surplus wire from the new reel into the looping pit.

The wire treating steps following feeding rolls 16 include cleaning, pickling, washing, plating, washing and drying, and these steps may be performed in separate compartments or units, or some or all of the steps may be performed in one continuous compartment separated into sections or chambers by suitable partition walls. For convenience, I have shown in Figure 1 all of the treatment steps except drying as being performed in a series of sections or chambers embodied in one unit.

The wires W pass from the feed rolls 16 preferably successively through a cleaning section 18, rinsing section 19, pickling section 20 and rinsing section 21. The rinsing sections may include high pressure water sprays and the cleaning and pickling sections may be electro-chemical units in which the cleaning and pickling solution is jetted against the wires by nozzles electrically connected to one side of a generator while the wires are electrically connected to the other side, as fully disclosed in my copending application Serial No. 326,632, filed March 29, 1940, and entitled Cleaning and pickling of metal surfaces, now Patent Number 2,372,599, patented March 27, 1945. However, any conventional cleaning, rinsing and pickling treatment may be used which will deliver the wires to the electroplating sections or units free of oil, dirt, oxides or other foreign matter.

The electroplating section preferably includes a plurality of identical plating units, two such units being shown generally at 22 in Figure 1, by way of example. Preferably at both ends of each unit 22, the wires W pass through pairs of contact rolls 23, later to be described in detail. Following the electroplating treatment, the wires are suitably rinsed in section 24, which may have high pressure water sprays if desired, and then pass through a dryer 25 and through the pulling rolls 17 to winding reels 26.

As previously stated, it may be desirable to interpose rinsing sections or units after each plating unit or to use alkaline and acid plating solutions alternately in the plating units, to adapt the invention for plating various metals or for plating thicker deposits. If such rinsing units are desired, they can be substantially the same as the rinsing sections or units 19, 21 and 24.

Referring now to Figs. 2 to 5 inclusive, one of the electroplating units 22 is shown mounted in a tank 27 having a lining 28 of rubber or other insulating material. For example, the plating unit 22 is shown as adapted for electroplating three wires, but it may be arranged for electroplating a larger or smaller number of wires as desired.

Each pair of contact rolls 23 preferably includes an upper roll 23a and a lower roll 23b having arcuate grooves 29 for contacting the upper and lower surfaces of the wires W as they pass between the rolls. The roll shafts 30a and 30b may be journaled in current conducting bearings

31 mounted in angular supporting arms 32 which are pivoted at the elevation of the wires in insulated bearings 33 secured to the sides of the tank 27. The upper ends of the arms 32 are adjustably secured preferably by bolts 34 passing through slots in the arms, to brackets 35 mounted on the tank 27 and insulated from the arms 32 as indicated at 36. If desired, the brackets 35 may be made of insulating material.

Thus, the pressure of the contact rolls on the wires W can be adjusted by loosening the bolts 34 and rotating the arms 32 about the pivots 33 to move the rolls 23a and 23b toward or away from the wires. As indicated diagrammatically in Fig. 2, the negative terminal of a D. C. generator G is connected to the arms 32 by a current conductor 38, which may be conveniently connected to the nuts 39 on bolts 34. Thus current passes from the generator G through the arms 32 and contact rolls 23a and 23b to the wires W. If desired, one of the rolls 23a and 23b may be an insulating roll such as a rubber covered roll or the like.

The electroplating unit 22 preferably includes 25 tubular preferably hollow cylindrical anodes 40, one surrounding or encircling each wire W between the pairs of contact rolls 23. The anodes are made of a metal which may either be soluble or insoluble in the plating solution. Each anode 40 is rotatably mounted in longitudinally spaced bearings indicated generally at 41 and supported on the floor of the tank 27. The bearings 41 may each include a bearing cap 42 of current conducting metal such as nickel which will withstand the corrosion effect of the plating solution and each cap 42 may have arcuate portions 43 for fitting around the anodes 40, with laterally projecting end flanges 44.

The bearings 41 also include bearing inserts 45 of insulating material such as micarta for fitting under the anodes 40 and supporting the weight thereof. The bearing inserts 45 are in turn suitably supported from the floor of the tank by means such as flanged plates 46 and 47 which are provided with apertures 48 and 49 respectively to allow free circulation of plating solution contained in the tank 27.

Means for yieldingly clamping the bearing caps 42 downwardly against the anodes 40 preferably includes studs 50 secured in plates 46 and projecting upwardly through flanges 44 of the bearing caps. Nuts 51 on the upper ends of the studs 50 compress springs 52 against the flanges 44 to urge the bearing caps downward against the anodes 40. As shown in Fig. 2, the positive side of the generator G is electrically connected by a conductor 53 to the anodes 40 through the bearing caps. Studs 50 are insulated from plates 46 by suitable insulation indicated at 50a.

Means for rotating the anodes 40 for subjecting every part of the wire surface within the anodes to the same electrodic conditions, preferably includes gears 55 one secured on each tubular anode 40, as by a key 56. The gears 55 mesh with each other as shown in Fig. 4, and one gear is driven by a pinion 57 mounted on a drive shaft 58 which is operatively connected to suitable driving means such as a motor (not shown). Gears 55 and pinion 57 are preferably of insulating material such as micarta, to prevent passage of the plating current therethrough.

Means for directing plating solution into the front ends of the anodes 40 and for guiding the wires in paths axially of said anodes preferably includes a nozzle 60 of insulating material such

as porcelain mounted at the front end of each anode. Each nozzle 60 preferably has a curved passageway 61 receiving a vertical supply pipe 62 at its upper end and discharging into the anode through an annular boss portion 63 which loosely fits in the front end of the anode. A guiding aperture 64 for the wire W intersects the passage 61 and is coaxial with the anode 40. Preferably a post or the like 65 supports each nozzle 60 from the floor of the tank.

At the rear or exit end of each anode 40 is mounted a discharge nozzle 66 of insulating material such as porcelain having a curved passageway 67, preferably of smaller cross section than inlet passageway 61 leading from an annular boss portion 68 loosely fitting in the discharge end of the anode, and the passageway 67 discharges vertically downward into the tank. A guiding aperture 69 for the wire W intersects the passageway 67 and is coaxial with the anode. A perforate support 70 may be provided for supporting the nozzle 66 from the floor while permitting plating solution to flow out of the nozzle into the tank.

Preferably, a solution slinger disk 71 is mounted on each end of each of the anodes 40, to prevent an excessive amount of plating solution from reaching the gears 55 and bearings 41.

In the operation of the electroplating units, as the wires W pass continuously therethrough, plating solution is maintained in the tank 27 at a suitable level such as indicated by the dot-dash line L, and is pumped from the tank through the conduit 72 by pump 73 through the heat exchanger indicated diagrammatically at 74, where the solution temperature is adjusted to the desired degree. From the heat exchanger 74 the solution is circulated through conduit 75 by suitable connections (not shown) to the inlet pipes 62 whence it flows through the rotating anodes 40 and back into the tank.

Any good commercial coating solution for electroplating the desired metal may be used. For example when plating zinc on steel, the following solution is very satisfactory:

	Oz./gal.
Zinc sulphate	48
Ammonium chloride	4
Sodium acetate	2
Glucose	16

While the plating solution is circulating through the rotating anodes, electric current flows from the generator G through the contact rolls 23 to the wires W, and from the wires through the plating solution to the rotating anodes and back to the generator.

If the anodes 40 are made of a metal which is insoluble in the plating solution, the metal content of the plating solution must be replaced as it is plated out of solution; whereas if the anodes are made of a metal which is soluble in the plating solution, then the anodes must be replaced as they are dissolved.

Due to the fact that the tubular anodes are closely and uniformly spaced from all sides of the wires at all times and the anodes are constantly rotating to provide uniform anode conditions all around the wire, a relatively low electroplating voltage may be used with a high current density to give an extremely high plating efficiency; and a uniform, adherent and fine-grained coating is produced on the wire. The circulation of the plating solution through the rotating tubular anodes provides for a minimum of polarization and hence substantially eliminates the accumulation of gas

along the wire which would otherwise produce rough deposits of the plating.

Accordingly, the present invention provides a high speed and economical way of producing electroplated wire having a uniform plating of high quality which will not peel or crack when the wire is bent sharply.

The fact that the wire travels at a high speed in a horizontal path makes it possible to plate heavy gauge wire in relatively light equipment, with a minimum of installation and maintenance cost.

For simplicity, I have confined the foregoing description to an arrangement of plating apparatus in a horizontal path. However, my invention is not intended to be limited to a horizontal path as the advantages thereof are also present regardless of the position of the anodes. When the anodes are not in a horizontal path it is necessary to provide rolls for guiding the wires in the desired path to maintain the wires concentric with the anodes.

I claim:

1. Apparatus for continuously electroplating wire and the like including a rotatable tubular electrode, means for rotating said electrode, means for passing wire continuously longitudinally in one direction through said electrode axially thereof, means for circulating electroplating solution through said tube from one end to the other, and means for passing electroplating current from the wire through said solution to said tubular electrode.

2. Apparatus for continuously electroplating wire and the like including a hollow cylindrical anode, means rotatably mounting said anode, means for rotating said anode, a nozzle mounted at one end of said anode for delivering plating solution into said anode, a nozzle mounted at the other end of said anode for discharging plating solution therefrom, means for continuously moving wire in one direction through said anode axially thereof while said anode is rotating, means for supplying plating solution to the delivering nozzle and means for passing an electroplating current through said solution between the wire and said anode.

3. Apparatus for continuously electroplating wire and the like including a hollow cylindrical anode, means rotatably mounting said anode, means for rotating said anode, a nozzle mounted at one end of said anode for delivering plating solution into said anode, a nozzle mounted at the other end of said anode for discharging plating solution therefrom, means for continuously moving wire in one direction longitudinally through said anode while said anode is rotating, both of said nozzles having means for guiding said moving wire axially of said anode, means for supplying plating solution to the delivering nozzle, and means for passing an electroplating current through said solution between the wire and said anode.

4. Apparatus for continuously electroplating wire and the like including a nozzle for delivering plating solution, an axially aligned nozzle longitudinally spaced from said delivering nozzle for discharging plating solution, a hollow cylindrical anode journaled at its ends on said nozzles, means for rotating said anode, means for continuously moving wire longitudinally through said anode in one direction while said anode is rotating, means for circulating plating solution from the discharging nozzle to the delivering

nozzle, and means for passing electroplating current from the wire through said solution to said anode.

5. Apparatus for continuously electroplating wire and the like including a hollow cylindrical anode, adjustably means rotatably mounting said anode, means for rotating said anode, means for continuously passing wire longitudinally in one direction through said anode axially thereof while said anode is rotating, means for circulating electroplating solution through said anode from one end to the other thereof, contact rolls engaging said wire, and an electric current generator connected in circuit with said contact rolls and said anode for passing electroplating current through said solution.

6. Apparatus for continuously electroplating wire and the like, including a hollow cylindrical anode, means rotatably mounting said anode, means for rotating said anode, a nozzle mounted at one end of said anode for delivering plating solution into said anode axially thereof and having a wire guiding opening axially aligned with said anode, a discharge nozzle mounted at the other end of said anode for discharging plating

25 solution therefrom and having a wire guiding opening axially aligned with said anode, means for continuously moving wire in one direction longitudinally through said nozzle guiding openings and said anode while said anode is rotating, and means for passing an electroplating current through said solution between the wire and said anode.

7. Apparatus for continuously electroplating 10 wire and the like, including a hollow cylindrical anode, means rotatably mounting said anode, means for rotating said anode, means for continuously passing wire longitudinally in one direction through said anode axially thereof while

15 said anode is rotating, means for circulating electroplating solution through said anode from one end to the other thereof, upper and lower contact rolls engaging said wire, means adjustably mounting said contact rolls for movement toward and away from said wire, and a generator connected in circuit with said contact rolls and said anode for passing electroplating current through said solution between the wire and said anode.

JOHN S. NACHTMAN.
